PAPER CONTAINER FOR DYNAMITE

Edwin A. Godfrey, Sacramento, Calif.

Application March 19, 1943, Serial No. 479,793

4 Claims.

(Cl. 102—24)

This invention relates to certain new and useful improvements in paper containers for dynamite and of the type wherein two or more sticks of dynamite may be assembled in the paper container to form a single charge.

The primary object of the invention is to provide a paper container for dynamite wherein two or more sticks of dynamite may be assembled to produce a single charge and in which the paper container is formed of interfitting end-connected sections that have interlocking connections with the dynamite sticks contained therein for securely holding the dynamite sticks against relative movements.

A further object of the invention is to provide a paper container for dynamite wherein the paper container is formed of interfitting end sections having a thread or like connection, with the male end of each section moved to a diameter less than the diameter of the remaining portion of the section when two sections of the paper container are assembled to provide an inwardly directed relatively wide annular shoulder on the paper container that interfits with an annularly reduced intermediate portion of a dynamite stick for holding the latter against sliding movements within the paper container.

With the above and other objects in view that will become apparent as the nature of the invention is better understood, the same consists in the novel form, combination and arrangement of parts hereinafter more fully described, shown in the accompanying drawing and claimed.

In the accompanying drawing:

Figure 1 is a fragmentary longitudinal sectional view of a paper container for dynamite constructed in accordance with the present invention, two dynamite sticks being fragmentarily illustrated and partly in section as confined within the container;

Figure 2 is a side elevational view of one section of the paper container, partly broken away and shown in section;

Figure 3 is an end view of one of the container sections, and

Figure 4 is a fragmentary sectional view showing the split male end of a container section expanded to permit introduction of a dynamite stick therewith.

Referring more in detail to the accompanying drawing, there is illustrated a paper container for dynamite sticks wherein the container is formed of sections interfittingly connected at adjacent ends, each section being designated in general by the reference character 5 and pref-

erably of cylindrical form although the same could have the intermediate body portion thereof polygonally formed.

The section 5 as clearly shown in Figure 2 has one end 6 thereof that will be hereinafter referred to as the female end, internally threaded as at 7, the end 6 being of the same diameter as the intermediate body portion of the section 5.

The other end of the section 5 designated in general by the reference character 8 constitutes the male end and is pressed or otherwise formed to provide a cylindrical end 9 of lesser diameter than the intermediate portion of the section 5. The male end 8 is longitudinally slit as

at 10 in circumferentially spaced relation, with the slits extending a short distance as at 10a into the central body portion of the section 5 while the outer face of the end 9 is provided with a thread 11 interrupted by the slits 10.

It is intended to assemble two or more dynamite sticks in a series of end-connected paper container sections 5, and as shown in Figure 1, two such dynamite sticks are illustrated as assembled in three paper container sections, each

dynamite stick being indicated by the reference character 12 and having a relatively wide annularly reduced neck 13 intermediate the ends thereof.

In placing a dynamite stick 12 in a paper container section 5, the stick is preferably inserted into the female end 6 and the diameter of the dynamite stick 12 is substantially the same as the internal diameter of the paper section 5 to have slight frictional contact therewith. Upon continued movement of the dynamite stick into the paper section 5, one of the ends of the stick, as shown in Figure 4, will move into the split male end 8 to expand the same as shown in Figure 4 for passage of the end of the stick, further movement of the stick within the paper section 5 positioning the reduced neck portion 13 thereof in registry with the male end 8, whereupon the sections of the split male end 8 will close or move towards each other and into the annularly reduced neck 13. A second paper section 5 then has the female end 7 placed over the projecting end of the dynamite stick and moved into threaded engagement with the male end 8 and when fully threaded thereon the two end-connected paper

sections assume the positions shown in Figure 1. The interfitting connection between the ends of the two paper sections 5 and their interlocking connection with the annularly reduced portion 13 of the dynamite stick 12 holds the latter against movements within the paper containers

and also holds assembled dynamite sticks against relative movements. It will be understood that two or more dynamite sticks may be assembled in a paper container as described to form a single charge.

While there is herein shown and described the preferred embodiment of the invention, it is nevertheless to be understood that minor changes may be made therein without departing from the spirit and scope of the invention as claimed.

I claim:

1. In a paper dynamite package of the character described, tubular paper sections telescopically connected at their ends with the overlapped portions providing an internal diameter in the zone thereof less than the diameter of the remaining portions of said sections, and dynamite sticks in the sections interlocked with the end connections between the paper sections intermediate the ends of the dynamite sticks.

2. In a paper dynamite package of the character described, tubular paper sections interconnected at their ends and dynamite sticks in the sections interlocked with the end connections between the paper sections intermediate the ends of the dynamite sticks, said end connections including telescoping threaded portions with the inner portion of the end connection extending into the bore of the connected tubular sections and the interlocking connection including an annular groove in the dynamite stick intermediate the ends of the stick with the inner portion of the end connection lying therein.

3. In a paper dynamite package of the character described, tubular paper sections interconnected at their ends and dynamite sticks in the sections interlocked with the end connections between the paper sections intermediate the ends of the dynamite sticks, said end connections including telescoping threaded portions with the inner portion of the end connection extending into the bore of the connected tubular sections and the interlocking connection including an annular groove in the dynamite stick intermediate the ends of the stick with the inner portion of the end connection lying therein, said inner portion being longitudinally split to permit expansion when placing a dynamite stick therein.

4. In a dynamite package of the character described, a series of end-connected tubular sections, each section having one end internally threaded and the other end annularly reduced, externally threaded, longitudinally split and extending in the bore of the tubular section for the threaded attachment of the internally threaded end of the adjacent section, and dynamite sticks in the container each having an annular groove intermediate its ends for reception of the inwardly extending portion of the reduced end of the tubular section to form an interlocking connection between the dynamite stick and the tubular sections to prevent axial movements of the dynamite stick in the connected tubular sections.

EDWIN A. GODFREY.
